(57) **CLAIM**

The ornamental design for a clutch retainer, as shown and described.

DESCRIPTION

FIG. 1 is a perspective view of a clutch retainer, showing its new design;

FIG. 2 is a front view thereof;

FIG. 3 is a top plan view thereof;

FIG. 4 is a back view thereof;

FIG. 5 is a right-hand side view thereof;

FIG. 6 is a reference front view thereof;

FIG. 7 is a sectional view taken along line 7-7 of FIG. 6; and,

FIG. 8 is an exploded perspective view of a clutch in which the retainer shown in FIG. 1 is used.
The bottom plan view and the left-hand side view are omitted because these views are mirror images of the top plan view and the right-hand side view respectively.
